US0D1002592S

(12) **United States Design Patent** (10) **Patent No.:** **US D1,002,592 S**
(45) **Date of Patent:** **** Oct. 24, 2023**

(54) **STAND FOR A LOUDSPEAKER**

(71) Applicant: **GENELEC OY**, Iisalmi (FI)

(72) Inventors: **Tommi Paavilainen**, Iisalmi (FI); **Harri Koskinen**, Helsinki (FI)

(73) Assignee: **GENELEC OY**

(**) Term: **15 Years**

(21) Appl. No.: **29/782,088**

(22) Filed: **May 4, 2021**

(30) **Foreign Application Priority Data**

Nov. 4, 2020 (EM) 008246284

(51) **LOC (14) Cl.** **14-01**

(52) **U.S. Cl.**

USPC **D14/229**; D14/224
